COIN OPERATED DISPENSING PUMP CONTROL

Filed Dec. 15, 1948

UNITED STATES PATENT OFFICE

2,664,983

COIN OPERATED DISPENSING PUMP
CONTROLSamuel H. Ellison, Washington, D. C., assignor
of one-half to Herman E. Mitschle, Chicago,
Ill.

Application December 15, 1948, Serial No. 65,479

8 Claims. (Cl. 194—3)

1

The present invention relates to dispensing pumps and more particularly to a novel means and mechanism for initiating the operation of a dispensing pump by the insertion of a coin of the proper denomination. Such a pump is preferably one for dispensing gasoline or liquid fuel and the present novel invention comprehends an attachment therefor which permits the purchaser to personally operate the pump and supply his wants after depositing the requisite coin or coins.

In view of the curtailed hours in which filling stations are open for service, it frequently happens that when a motorist is travelling in the evening or late at night, or on Sundays or holidays, his supply of gasoline becomes alarmingly low and he has difficulty in locating a filling station that does not adhere to the usual closing hours and is open for business.

Were the pumps at such filling stations equipped with a positive and accurate means for self-service whereby the motorist may purchase his requirement of gasoline by inserting one or more coins of prescribed denominations and personally operate the dispensing or vending pump to withdraw the quantity of gasoline for which he has paid, it will be appreciated that such an attachment would fill a long felt need for both the service station proprietor as well as for the motorist. It would allow the service station proprietor to dispense gasoline after closing hours without the expense of having an attendant available, and it would allow the motorist to purchase any desired quantity of much needed gasoline at the then prevailing rate.

It is, therefore, an object of the present invention to provide a novel device to be applied or attached to a gasoline dispensing or vending pump whereby the pump may be actuated by the motorist and thus make it self-serving.

The present invention further comprehends a novel means and mechanism in the form of a relatively simple and coin-initiated attachment adapted to be applied or connected to the computer shaft of any standard make of gasoline vending pump, and permit the motorist to personally supply his automobile with a quantity of gasoline, the quantity depending upon the denomination and number of coins deposited. Upon the insertion of the coin or coins, the pump is made operative and it is a relatively simple matter for the motorist to supply his wants and with the assurance that he is securing the quantity designated and is not paying a premium for the amount dispensed.

Although the present novel attachment is par-

2

ticularly advantageous in making gasoline available to a motorist when the service station is normally closed for business, its use is not so limited but when installed upon a plurality of pumps, the owner or attendant at a service station is capable of supervising or servicing a much larger number of automobiles than would be possible under the present system and without requiring additional help in operating the pumps.

A still further object of the present invention is the provision of a novel means and mechanism synchronized with the operation of the computer head of any standard or commercial make of gasoline dispensing or vending pump for converting the pump from one requiring an attendant to one that is self-serving and operated by the motorist upon the insertion of a coin of predetermined denomination.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawing, and while there is shown therein a preferred embodiment, it is to be understood that the same is susceptible of modification and change and comprehends other details, arrangements of parts, features and constructions without departing from the spirit of the invention.

In the drawing:

Figure 1 is a view in side elevation of a standard or commercial type of gasoline dispensing pump to which the novel invention has been applied, parts of the outer housing of the pump assembly being broken away to more clearly disclose the present invention.

Fig. 2 is a fragmentary view in front elevation of the dispensing pump assembly of Fig. 1, the front and a side of the pump housing and other parts being broken away for a more complete understanding of the coin operated mechanism.

Fig. 3 is a fragmentary enlarged view, part in side elevation and part in vertical cross section, of the latch and switch assembly and their associated parts which are automatically initiated by the motorist in the dispensing of the gasoline.

Referring to the disclosure and more particularly to the novel embodiment shown in the drawing as illustrative of the present invention, the pump 1 therein shown and adapted to be converted to a coin operation, may be of any stand-

ard or commercial design and construction in which the pump is provided with a computer head 2. One form or arrangement and location of such computer head is shown in the illustrative drawing, it being understood however, that there may be a variation in the arrangement and location of the associated parts.

On the computer head 2 is a shaft 3 carrying a so-called "money" wheel 4 adapted to be driven by the gasoline meter. In some pumps this shaft makes one revolution for each ten cents worth of gasoline delivered, while in others the amount delivered in each revolution of the shaft 3 may be twenty-five cents worth. However, in each of these pumps the variations in price of the gasoline per gallon are corrected or compensated for in the transmission located generally just below the computer head and associated therewith. If the shaft 3 makes one revolution for each ten cents worth of gas delivered and the pump is converted to a coin operation of twenty-five cents, this motion is geared through a two and one-half to one reduction to thereby rotate a crank or eccentric through one revolution whereby to adapt it to an operation initiated by the deposit of a twenty-five cent piece. Part of the "money" shaft 3 is rotated when the reset crank, with which all such pumps are supplied to restore the pump to a zero reading after a customer has been served, has been operated. The present novel coin attachment is located ahead of the reset clutch whereby this part of the shaft rotates only when gasoline is being delivered.

The train of gears diagrammatically illustrated as associated with and at each side of and below the crank or eccentric 5, are standard gear assemblies in the computer heads of standard makes of gasoline dispensing pumps and therefore are not illustrated in detail. However, it is to be understood that the crank or eccentric 5 and its drive shaft are co constructed, arranged and related to the shaft 3 that the crank or eccentric rotates through a complete revolution for each coin deposited.

The crank or eccentric 5 is connected to a substantially vertically arranged crank arm or link 6 and a substantially horizontally arranged lever arm or bar 7 pivotally mounted at one end to a bracket 8, whereby the motion of the eccentric is reduced to a substantially rectilinear motion through the crank and link assembly.

Associated with the outer end 9 of the lever arm or pivot bar 7 is an upstanding latch rod 11 of a latch assembly 12. This latch assembly is provided with a substantially vertically positioned bar 13 pivotally mounted at its lower end upon a switch 14 for operating the motor A which in turn operates the computer head and actuating mechanism of the pump. Intermediate its length this bar 13 is provided with a latch 15 including a single direction latch member or dog 16 freely pivoted at 17 upon a base or supporting plate 18 affixed to or formed integral with the bar 13. The latch member or dog 16 is confined within a bracket 19 secured to the base or supporting plate 18 by screws or other attaching means 21.

The latch assembly 12 is movable bodily and laterally but is limited or confined in its inward lateral movement by a bracket 22 and in its outward lateral movement by a spring 23 having one end attached to the bar 13 and the other end secured to the housing or other fixed part of the pump. This latch assembly 12, eccentric 5 and associated parts, are so arranged, related and their movements so synchronized that when the

pump is not being operated the upper end of the latch rod 11 is located in a position directly beneath the outer end 9 of the lever arm or bar 7, and the latch assembly 12 including the latch rod 11 and bar 13 is held against vertical movement until released. This in turn prevents the switch 14 from being rotated to energize the motor A. In this latched, inoperative position, the cam 5, link 6 and lever arm 7 are moved to their lowermost position in which the cam is moved approximately 180° from the position shown in Figs. 1, 2 and 3, and the lever arm 7 is disposed in a substantially horizontal plane.

To move the entire latch assembly 12 bodily and laterally (to the left in Figs. 2 and 3) against the tension of the spring 23, the tapered surface 24 on the latch or dog 16 is engaged by the outer or free end of an elongated trip member or lever arm 25 (Fig. 1) clamped or suitably secured at the other end to an end of a shaft 26 projecting from a coin box 27 mounted at or in a wall of the pump housing. This shaft is rotated by a handle 28 disposed at the front of the coin box, the latter being of any suitable or standard construction provided with a coin slot or slots 29 and a bent coin return slot 30, the handle or operating member 28 and the shaft 26 being adapted to be rotated or actuated by rotating the handle through a limited arc and in a clockwise direction when facing the front of the box. The arc of movement of the shaft 26 is such as to cause the free end of the lever arm or trip member 25 to engage the tapered surface 24 on the latch or dog 16 and thereby move the latch assembly 12 bodily to the left as viewed in Figs. 2 and 3 and against the tension of the spring 23 an amount sufficient to dislodge the upper end of the latch rod 11 from beneath the outer end 9 of the lever arm or bar 7.

When the latch rod 11 is dislodged from beneath the end 9 of the lever arm or bar 7 and moved to one side of the latter (see dotted line position in Fig. 3), the entire latch rod assembly 12 is permitted to rise vertically and the switch 14 is in a position to be rotated to start the pump upon operation of the hose hanger hook or bracket in the manner to be later more fully explained. As the motorist allows the fluid to flow by operating the conventional valve on the end of the hose, the crank or eccentric 5 is permitted to rotate through a complete revolution. During the initial rotation or arc of movement of the eccentric or crank 5, the outer end 9 of the lever arm or bar 7 is released and free, but as the lever 7 nears the top of its travel the upper end of the latch rod 11 is drawn or moved laterally under the end 9 of the lever arm 7 by the spring 23 where it is in position to be engaged by the lever 7 on its downward stroke. This is the full line position in Fig. 3 and also in Figs. 1 and 2, wherein is shown the position of the lever arm 7 and the latch bar 11 at the apex of the arc of movement of the lever arm and at substantially the instant when the end 9 of the arm 7 engages the upper end of the latch rod 11, the latter having been moved into this position by the spring 23. This engagement forces the latch rod assembly 12 downwardly whereby the bar 13 rotates the switch 14 which shuts off the pump motor. A suitable spring (not shown) is preferably provided to move the switch 14 in counter-clockwise direction.

Adjustably mounted upon the latch rod 11 by a set screw and spaced from its upper end is a collar 31, and at the lower end of this rod is pro-

vided a relatively light compression spring 32 seating against and disposed between an enlargement or piston 33 on the lower end of the latch rod and the upper end of a projection 34 provided at the upper end of the latch bar 13. The enlargement or piston 33 is slidably mounted within the upper portion of a cylinder or tubular housing 35 provided between an upper face plate or cap 36 and a lower face plate 37. These face plates are disposed and held in spaced relation by tie rods 38 threaded at their lower ends 39 for adjustment and locked in their adjusted position by lock nuts 41.

The upper face plate 36 is provided with an upstanding sleeve 42 apertured for reception and movement of the sliding latch rod 11 and the lower face plate 37 is provided with an upstanding sleeve or collar 43 for receiving the lower end of the tubular housing 35. Encompassing this tubular housing is a relatively heavy compression spring 44 having its opposite ends abutting the lower side of the upper face plate and the upper end of the collar or sleeve 43 on the lower face plate.

Further lowering of the lever arm or bar 7 from the full line position in Fig. 3, depresses the latch rod 11 until the collar 31 engages the upper end of the upstanding sleeve 42 and which is just prior to the lower end of the stroke or arc of revolution, after which further movement of the lever arm or bar 7 and collar 31 against the sleeve 42 depresses this sleeve and the head or upper face plate 36 against the relatively heavy compression spring 44. Thus during all but approximately the last one-eighth of the revolution or arc of movement of the eccentric or crank 5 and after the collar 31 engages the sleeve 42, the latch rod 11 is depressed against the pressure of the relatively light compression spring 32, but during the remainder of the arc of travel of the crank or eccentric 5 at the end of its revolution further downward movement of the latch bar 11 and latch assembly is against the compression of the heavier spring 44.

This spring assembly serves a dual purpose. First, it allows very little strain on the eccentric or crank 5 when the latter is at the apex of its downward or approximately last one-half revolution at the time when there is the least leverage action. Second, it shuts off the motor switch 14 with greater snap action after it engages the outer and heavier compression spring 44 and allows no over-travel of the money wheel 4. In addition, the outer or heavier compression spring also takes up any shock set up by the latch assembly and associated parts after the motor switch 14 shuts off. Both the inner and outer compression springs are adjustable for variations in machining and assembling tolerances.

Also connected to the switch 14 is one end of a switch lever 45, the other end of this lever being connected to a pivotally mounted hose mounting or hook 46 adapted to receive and retain the nozzle of a dispensing hose 47 when the pump is not being operated. These parts are standard equipment on gasoline dispensing pumps of the manually controlled, electrically operated type for initiating the operation of the pump when the nozzle is removed from the hook 46 and the lever or arm 45 is moved or depressed to actuate the switch 14. However, with the present invention the mere removal of the hose nozzle will not trip the switch and energize the motor unless and until the requisite coin has been deposited in the slot 29 and the handle 28 and its shaft 26 have

been turned to the limit of their movement whereby the latch rod 11 is moved from beneath the lever arm 7.

Upon release of the handle, a spring or other suitable tension means returns the handle and shaft to inoperative position. Such movement is permitted by reason of the free pivotal movement of the latch member or dog 16 in an upward direction so that the lever arm or trip member 25 rides over this latch or dog as the handle 28 and shaft 26 are returned to inoperative position by rotation in a counter-clockwise direction. As in the operation of the present standard or commercial forms of pumps, gasoline is not dispensed until the attendant or motorist has inserted the nozzle into the gas tank and has actuated the usual trigger or other valve controlling mechanism generally positioned on the nozzle for controlling the flow.

In the operation of the present device, the nozzle (not shown) and hose are removed from the hook 46 and the nozzle inserted into the gas tank. A coin of proper denomination is inserted into the slot 29 and the handle 28 is rotated clockwise through an arc of approximately 45°. This actuates the latch assembly 12 whereby the lever arm or trip member 25 moves the latch member or dog 16 and the entire latch assembly to the left as viewed in Fig. 2 and to the dotted line position of Fig. 3. Such movement removes the latch rod 11 at the upper end of the latch assembly from beneath the outer end 9 of the lever arm or bar 7, whereupon the pivotally mounted switch 14 for energizing the motor A is rotated in a counter-clockwise direction from its off position to a position in which the switch lever 45 is depressed and the latch bar 13 and latch assembly 12 are raised. The motor A is thus started but the designated quantity of gasoline is not dispensed except as the valve actuating means on the hose nozzle is operated and the money wheel 4 is rotated in the usual manner.

As gasoline is delivered, the crank or eccentric 5 rotates through a complete revolution (Figs. 1 and 2 showing the crank after it has rotated through approximately one-half of its revolution), and when it is again at the bottom of its stroke after completing one revolution the latch rod 11 is disposed beneath the end 9 of the lever arm or bar 7. When in the latter position the switch 14 is thrown to open position and the operation of the pump is stopped. As in the present manually controlled pumps, opening of the switch 14 to deenergize the circuit to the motor is so timed or related to the dispensing operation that the pump automatically and instantaneously ceases operation when the requisite or predetermined quantity of gasoline has been metered. In the present device, the switch is opened by the latch assembly 12 when the lever arm or bar 7 has reached its lowermost point of travel.

Assuming that the operation of the pump is initiated by the insertion of a twenty-five cent coin, the computer head will show that amount of gasoline delivered at the conclusion of the dispensing operation. The pump may thereafter be reset to zero reading, or the motorist may insert one or more additional coins and after each subsequent delivery the total or aggregate purchase will appear on the computer head.

It will be understood that the present invention is applicable to coins of any desired denominations, the only requirement being that the amount of the coin selected to initiate the opera-

tion and the rotation of the crank or eccentric 5 be synchronized with the money wheel 4 on the computer head. Also, if the attachment is to function only at certain times and the pump so equipped be operated manually by an attendant at other times, it is intended that means be provided for disengaging or disconnecting the attachment at such times that an attendant is present and dispenses the gasoline. This may be simply accomplished by holding the latch rod 11 and latch assembly 12 from its association with the lever arm 7 and the crank or eccentric 5.

Although I have more particularly referred to the dispensing of gasoline, it is to be understood that the invention is not limited thereto but may be employed in the self-serving of fuel oil, etc.

Having thus disclosed the invention, I claim:

1. In a coin operated dispensing apparatus including a manually controlled and motor operated gasoline dispensing pump, a computer head, a switch for operating the motor, manually actuated means for closing the switch to operate the motor, and control mechanism for rendering the switch inoperative except upon the deposit of a designated coin, said mechanism including an eccentric connected to the computer head and rotated through one revolution each time an amount of gasoline is dispensed equal to that of a designated coin, latching mechanism connecting the switch and eccentric and automatically opening the switch at the end of each revolution of the eccentric, means for maintaining the latching mechanism engaged and the switch in open position, and a coin operated device including a manually operable handle and a trip member for disengaging the latch mechanism when the handle is turned after depositing a designated coin whereby the switch is movable to closed position to operate the pump only upon depositing a designated coin.

2. In a coin operated dispensing apparatus including a manually controlled and motor operated gasoline dispensing pump, a computer head provided with a money wheel designating the cost of the gasoline dispensed, a switch for operating the pump motor, a hook connected to the switch for normally closing the switch to operate the motor when the hook is elevated, and mechanism for rendering the switch inoperative except upon the deposit of a designated coin and including a rotatable crank member connected to the computer head and rotated through one revolution each time an amount of gasoline is dispensed equal to that of the designated coin, a lever arm attached to said rotatable crank member, latching means connected to the switch and actuated by the lever arm for automatically opening the switch and stopping the pump at the end of each revolution of said rotatable member, means for maintaining the latching means in engagement with the lever arm to retain the switch open until another designated coin is deposited, and a manually operated, coin controlled means provided with a trip member for releasing the latching means and permit closing of the switch to operate the motor by elevating the hook only upon the insertion of the designated coin.

3. In a coin operated gasoline metering and dispensing pump of the manual control and motor operated type including a gasoline meter, a computer head provided with a money wheel driven by the gasoline meter, a switch for operating the pump motor, mechanism for tripping the switch to operate the motor and dispense the gasoline,

and mechanism for rendering the switch inoperative except on deposit of a designated coin, said mechanism including a coin control means having a coin box in which the coin is deposited, a handle, a rotatable actuating shaft operable by the handle upon deposit of the designated coin, an elongated trip member secured at one end to the shaft and rotatable therewith and the other end free, latch mechanism connected to the switch, an eccentric connected to and synchronized with the rotation of the money wheel and rotated by the meter through one revolution for each designated coin deposited, and an arm connected to said eccentric and adapted to be engaged by the latch mechanism for moving and retaining the switch inoperative, the free end of said trip member engaging and releasing said latch mechanism from engagement with the arm to permit the motor switch to be moved to closed position to operate the pump after deposit of a designated coin and rotation of the handle and its shaft.

4. In a coin operated dispensing apparatus including a manually controlled and motor operated gasoline dispensing pump, a computer head provided with a money wheel, a switch for operating the pump motor, means for closing said switch to operate the motor and pump, and control mechanism for rendering said switch closing means inoperative except upon the deposit of a designated coin, said mechanism including a member rotated in synchronism with the money wheel and for each revolution of said member a quantity of gasoline represented by the amount of the coin deposited is dispensed, an arm connected to said member, latching mechanism connected to the motor switch and adapted to be engaged by the arm at the end of each revolution of the rotating member for causing the latching mechanism to open the switch and stop the operation of the pump, a coin operating device for tripping the latch mechanism and disengaging it from the arm, and tension means for returning the latch mechanism to a position to again be engaged by the arm.

5. In a coin operated and motor driven liquid dispensing pump, a computer head for automatically measuring the quantity of liquid dispensed and designating the cost thereof, a switch for controlling operation of the pump motor, means for closing said switch to operate the motor, and control mechanism for rendering said closing means inoperative except upon deposit of a designated coin, said mechanism including a shaft connected to the computer head and rotatable only when liquid is being delivered by the pump, a crank carried by said shaft, a lever arm connected to the crank for converting the rotation of said crank into a rectilinear motion, a latch mechanism including a part connected to and controlling the operation of the switch and a latch rod adapted to be engaged and depressed by the lever arm for causing said latch part to open the switch, and means manually operable by the motorist after the coin has been deposited for engaging and tripping the latch mechanism to disengage the rod from beneath the lever arm and permit the switch to close and operate the pump until the latch rod is again engaged and depressed by the lever arm at the end of a complete revolution of the crank and the latch part opens the switch and stops the operation of the motor.

6. In a coin operated and motor driven liquid

dispensing pump, a computer head for automatically measuring the quantity of liquid dispensed and designating the cost thereof, a switch for controlling operation of the pump motor, means for closing said switch to operate the motor, and control mechanism for rendering said switch closing means inoperative except upon deposit of a designated coin, said mechanism including a shaft connected to the computer head and rotatable only when liquid is being delivered by the pump, a crank carried by said shaft, a lever arm connected to the crank for converting the rotation of said crank into a rectilinear motion, a latch assembly having an arm connected to the motor switch for controlling the operation of the motor and a latch rod adapted to be engaged by said lever arm and at the end of its stroke open the motor switch, and a coin operating means including a manually controlled shaft and tripping member for releasing the latch rod from the lever arm whereby to permit operation of the motor and pump upon depositing a designated coin.

7. In a coin operated dispensing apparatus including a manually controlled and motor operated gasoline dispensing pump, a computer head, a switch for controlling operation of the motor, means for operating said switch, and control mechanism for rendering said switch operating means inoperative except upon deposit of a requisite coin, said mechanism including a coin operating device having a shaft and a tripping member manually operated by the motorist upon the insertion of a coin, a latch assembly moved to disengaged position by said tripping member upon rotation of the shaft and connected at one end to the motor switch and at the other end provided with a latch rod, a shaft and a crank connected to the computer head and operable only when gasoline is being dispensed by the pump, a bar pivotally mounted at one end and having its other end free, a crank arm connecting the crank to the bar for converting the motion of the crank to a rectilinear motion of the bar, the free end of said bar being disposed adjacent the end of the latch rod, and means for moving the latch assembly into engaging position where the latch rod is engaged by the free end of the bar and moves the latch assembly to open the motor switch at the completion of

each revolution of the crank, and retaining the latch assembly in said engaging position until another coin is inserted and the handle and tripping member are again manually operated to disengage the latch assembly and its latch rod from engagement with the free end of the bar.

8. In a coin operated and motor driven liquid dispensing pump, a computer head for automatically measuring the quantity and designating the cost of liquid dispensed, a motor switch normally opened upon removal of the dispensing hose for operating the pump, and control mechanism for rendering the motor switch inoperative except upon deposit of one or more coins of a predetermined denomination, said mechanism including a shaft connected to the computer head and rotatable only when liquid is being delivered by the pump, a crank carried by said shaft, a lever arm connected to the crank for converting the rotation of said crank into a rectilinear motion, a latch assembly having an arm connected to the motor switch for controlling the operation of the switch and a latch rod adapted to be engaged and depressed by the lever arm for moving the latch arm to open the motor switch when the crank has rotated through a complete revolution, a coin controlled shaft and tripping member for disengaging the latch assembly and dislodging the latch rod from the lever arm whereby the latch assembly is moved in a direction to close the motor switch and permit the pump to dispense a predetermined quantity of liquid in accordance with the coin deposited, and means for returning the latch rod to a position to be engaged by the lever arm.
